(57) **CLAIM**

The ornamental design for an aircraft delta fin, as shown and described.

DESCRIPTION

FIG. 1 is a rear, top perspective drawing of an aircraft delta fin showing our new design and its environment.

FIG. 2 is a detailed rear, top perspective view thereof;

FIG. 3 is a right side perspective view thereof;

FIG. 4 is a left side perspective view thereof;

FIG. 5 is a back plan view thereof; and,

FIG. 6 is a bottom plan view of thereof.

The portions of the drawings shown in broken lines indicate surrounding structure and environment that forms no part of the claimed design.

1 Claim, 6 Drawing Sheets
